UNITED STATES PATENT OFFICE

EDWARD BURTON, OF ROCKFORD, ILLINOIS, ASSIGNOR TO NATIONAL LOCK CO., OF
ROCKFORD, ILLINOIS, A CORPORATION OF DELAWARE

DESIGN FOR A LATCH

Application filed April 20, 1931. Serial No. 39,562. Term of patent 3½ years.

To all whom it may concern:

Be it known that I, EDWARD BURTON, a citizen of the United States, residing at Rockford, in the county of Winnebago and State of Illinois, have invented a new, original, and ornamental Design for Latch, of which the following is a specification, reference being had to the accompanying drawings, forming part thereof.

In the drawings:

Fig. 1 is a front elevation of a latch embodying the design of this invention,

Fig. 2 is a side elevation of the latch shown in Fig. 1, and

Fig. 3 is a top plan view.

I claim:

The ornamental design for a latch, as shown.

EDWARD BURTON.
